(57) **CLAIM**

The ornamental design for a wall mounted luminaire, as shown and described.

DESCRIPTION

FIG. 1 is a perspective view of the wall mounted luminaire showing the front, top and right side of the design;

FIG. 2 is a front elevation view of the design;

FIG. 3 is an elevation view showing the left side of the design, the right side of the design being the mirror image thereof;

FIG. 4 is a rear elevation view of the design;

FIG. 5 is a top plan view of the design; and,

FIG. 6 is a bottom plan view of the design.
